RAILWAY HOPPER CAR

Eduardo M. Damy, Antigua Camino a los Colomos
No. 500, Guadalajara, Jalisco, Mexico
Filed Sept. 8, 1958, Ser. No. 759,794
3 Claims. (Cl. 105—248)

The invention relates to an improvement in doors or outlets employed, for example, in connection with railroad cars. One purpose is to provide a door that can be easily adapted to a regular hopper car when employed, for example, to dump and spread ballast.

Another purpose is to provide an arrangement of outlets or chutes and controls therefor which will permit a precise and controlled delivery of ballast in the desired relation to one or both rails of a track.

Another purpose is to provide improved means for raising and lowering chute doors for hopper cars and the like.

Another purpose is to provide means for preventing the delivery of ballast to the top or head of a rail, while permitting delivery of ballast at each side of a rail.

Another purpose is to provide in a multi-hopper car control means for selectively opening one or more hoppers.

Another purpose is to provide means for selectively delivering ballast along either or both rails of a track.

Other purposes will appear from time to time in the course of the specification and claims.

The invention is illustrated more or less diagrammatically in the accompanying drawings wherein:

FIGURE 1 is a partial perspective view of a hopper car;

FIGURE 2 is a partial vertical, transverse section through the discharge hoppers shown in FIGURE 1, with the gates removed;

FIGURE 3 is a partial top plan view, on an enlarged scale in relation to FIGURE 2, of the control structure partially shown at the top of FIGURE 2;

FIGURE 4 is a section taken along line 4—4 of FIGURE 3, on an enlarged scale; and

FIGURE 5 is a fragmental detail view along section line 5—5 of FIGURE 3.

Like parts are indicated by like symbols throughout the specification and drawings.

Referring to the drawings, A generally indicates any suitable car body, such as an open-topped gondola, the details of which do not of themselves form part of the present invention. Illustrated in FIGURE 1 are two chutes, generally indicated as B, B. It will be understood that any number of chutes may be employed. It is convenient, for example, to provide another pair of chutes, which, if shown, would be beyond the left end of FIGURE 1, the second pair of chutes being inclined downwardly toward the first pair. In such case, with the employment of four chutes, two would be located over each of the track rails C. The details of the chutes are not of themselves important. Each chute may, for example, include generally vertical side walls 1, 2, and a downwardly extending bottom wall, not shown in detail in the drawings but extending along the edges of the side walls 1 and 2, as indicated at 3 in FIGURE 1. A convergent front wall 4 completes the hopper, which is provided with a discharge outlet or opening 5, as shown in FIGURE 2, but which is masked or closed by the gates or closures indicated in FIGURE 1.

While a wide variety of closures may be employed, a practical closure consists of a gate structure, generally indicated at 6 in FIGURE 1. Each such gate 6 has end portions or walls 7 to which may be secured levers 8 pivoted, as at 9, to the gondola A or to the upper part of the hopper B. It will be understood that each hopper has a gate 6 mounted at each end upon a lever 8, the levers

2

8 of each hopper being mounted for rotation about concentric horizontal axes, one of which is indicated at 9 in FIGURE 1. It will be understood that the parts are so constructed that when ballast or other material is being delivered into the hopper and against the gates 6 the thrust of the material, supplementing the weight of the gate structure, tends to move the gate 6 into the closed position of FIGURE 1.

It is important to provide means for selectively raising the gates 6 of the various hoppers B, either to open them completely for full discharge or to leave them at some intermediate position for partial discharge. It is also important that the gates be selectively controllable so that one or more of the gates and, if desired, all of the gates, can be simultaneously moved to a desired position. The desired flexibility of control includes the ability to close some gates while others are open, and to vary the setting of individual gates from the fully closed to the fully open position. Whereas the invention is applicable to a wide variety of uses, it is herein shown primarily in connection with the delivery of ballast from a ballast distributing car, to areas along the rails of a railroad track.

In considering the control mechanism, and with reference primarily to FIGURES 2 to 6, inclusive, two rotatable control rods or shafts 10 are indicated, each operable by a hand wheel at each end of each of the rods 10, although, for simplicity in disclosure, only one end of the rods 10 is shown in FIGURE 3. Anchored on each rod are two chains 12 which, when the wheels 11 of FIGURE 1 are rotated, are reeled in about the appropriate rod 10. A suitable hook or the like 6b may be connected to the gate 6 adjacent the lower end. The hook is of such a size that the chain may be looped or passed therethrough, as shown in FIGURE 1, or it may swing free.

The opposite end of each chain may be secured to an upper securing bracket 6a which may be mounted adjacent the top of the gate 6.

As will be clear from FIGURE 1, both wheels 11 can normally be rotated in opposite directions. In the particular structure herein shown the rotation of the wheels will eventually put tension on the chains 12. When the wheels 11 have been given sufficient rotation the result will be, after the full tensioning of the chains 12, to lift the gates 6 about the pivots 9 and against the thrust of the material in the hoppers. The operator can raise any particular gate as far as he wishes, from the fully closed position to the fully open position. When he stops rotating the appropriate wheel 11 in clockwise direction, referring to the position of the parts as shown in FIGURE 4, a locking means including a dog 15 in engagement with the ratchet wheel 16 on the shaft 10 prevents any retrograde rotation. Thus the operator can set the gates at any desired elevation and can leave them in that setting.

Where the operator, as in the pair of gates controlled by one of the shafts 10, wishes to open one while leaving the other closed, he has only to remove the chain from the hook 6b of the gate which he does not wish to open. When he leaves the chain in the hook 6b of a gate, that gate will be elevated, since the chain 12 will be put under tension. The operator can control the amount of opening by simply ceasing rotation of the appropriate wheel 11 when the controlled gate has reached its desired open position. If the opposite gate controlled by the same shaft 10 is disconnected, then it will stay closed. Or, alternatively, if the chain for the opposite gate is not passed through the hook 6a, then the chain will remain slack during the opening of the first gate. It is, of course, possible to so control or vary the length of chains employed to provide, if desired, that when one gate is fully elevated the other gate is still closed, if the chain is passing through the hook of the first gate, and not through the hook of the second gate. Or, when the first gate is

elevated to a predetermined degree, the second gate may be elevated to a substantially less degree. It is thus clear that the operator may so employ the above described control system as to elevate simultaneously all of the gates to a predetermined equal degree. On the other hand, it is possible for the operator to elevate a single gate while leaving the other gates closed. Or the operator may elevate the gates above one rail while leaving closed the gates aligned above the opposite rail. Or the operator may elevate some gates to a maximum opening, while moving other gates to a partly open position.

Whatever arrangement of gate opening the operator may desire, the elevated gate or gates may be promptly returned to the closed position merely by releasing the dogs 15 from the ratchet wheels 16 of one or both of the rods 10. This can easily be done, for example, by the use of appropriate control or release rods 20, of which, as in FIGURE 3, two are shown, one for each of the rods 10. The control rods are shown as rotatable about axes spaced laterally from but parallel with the axes of the rods 10. The details of the control structure may be widely varied but the convenient arrangement is to provide each of the control rods 20 with an easily accessible actuating lever 21.

With reference to the position of the parts as shown in FIGURE 4, if the lever 21 is moved into a counterclockwise direction it rotates the appropriate control rod 20 and raises a small actuating lever 22 which raises the right end of the dog 15 and thus elevates the tooth of the dog from contact with the opposed ratchet 16. This permits the associated rod 10 to rotate in a counterclockwise direction, referring to the position of the parts as shown in FIGURE 4. This retrograde rotation releases the chains, and their support is withdrawn from the gate or gates 6 which drop under the influence of gravity or under the influence of the thrust of material in the hopper B, or both. It will be understood, of course, that any suitable means may be employed for spring-biasing the dogs 15, if desired. The lever 21 may pass through a suitable bracket 23 mounted on the frame of the car to determine the limits of movement of the lever. As shown in FIGURE 3, the control rods 20 are positioned to be rotated in opposite directions, one clockwise and the other counterclockwise, to release the pawls from the ratchets. In FIGURE 1, the lever 21 on the right side must be moved counterclockwise to release the right gate, and the lever on the left side must be moved clockwise to release the left gate. Thus, to release a door, the lever is moved toward the door to be closed.

To prevent the undesirable positioning of ballast on rail tops, a deflector is provided for each hopper, in the line of flow of the ballast. Each such deflector F may, for example, include an angular body portion formed by two upwardly convergent surfaces 25. End members 26, 27 are provided, of which one, end member 27, is, in FIGURE 1, indicated as secured to the hopper structure or to a suitable cross-bar or member 28, shown in FIGURE 1 as extending across both hoppers. Since the deflectors F are spaced slightly above the rails, and are aligned along the rails, their effect is to split the stream of material delivered from the appropriate hopper, so that some of the ballast will flow outside of the rail and some inside of the rail over which the particular deflector structure F is aligned. None of the ballast will be delivered to or rest upon the top or head of the rail, but the ballast will be closely delivered either just within or just without the rail.

It will be realized that whereas a practical structure has been shown, nevertheless many changes may be made without departing from the spirit of the invention. The description and drawings are therefore to be taken as in a broad sense illustrative or diagrammatic rather than as limiting the invention to the particular disclosure herein made. For example, it will be realized that whereas the invention has been described and shown in connection

with a ballast car or gondola usable for delivering ballast to track surfaces, the invention may be applied for other purposes. The deflectors 25 may be otherwise than for preventing deposit of ballast to rail heads. The hopper closures may be employed at any desired location on the vehicle. A wide variety or number of hoppers may be employed. Whereas four hoppers inclined toward each other, two being aligned over each rail, provide a practical structure, two hoppers or even but a single hopper may be employed, depending upon the desired use.

Whereas the invention has been described in connection with railroad cars, it will be understood that it may be applied also to trucks, for example, dump trucks. Such dump trucks may be provided with hopper discharges and when so provided are useful, for example, for patch-work on roads.

The use and operation of the invention are as follows:

Assuming the application of the invention to the distribution of ballast over railroad tracks, the structure herein illustrated provides a suitable number of hoppers aligned over each rail of a railway track. A practical arrangement, as earlier described, is to provide two hoppers over each rail. Assuming that the purpose is to deliver ballast along the rails, each hopper is provided with an angular guard or deflector structure F which deflects the ballast, part to the outside of the rail and part to the inter-rail space, while preventing deposition of ballast on the rail head. Each pair of hoppers, one over each rail, is herein shown as controlled by a single elevating shaft. Each such shaft may be manually controlled by the use of one of the wheels 11 keyed or secured to the shaft. In larger installation servo motors or the like may be employed, but are not normally necessary. The result of the rotation of the shaft in the proper direction is to wrap around the shaft the hopper door elevating chains. Assume that both chains are secured to the lower brackets 6b of the associated hopper gates 6, then continuing rotation of the wheel 11 will elevate both gates. As above mentioned, the control system can be so adjusted that either gate may be elevated, or both gates may. The same is, of course, true of each of the pairs of gates provided. The operator has a complete and flexible control of the whole system. He merely has to rotate the wheels 11 in a proper direction to raise as many of the gates as he wishes to raise. And the levers 21 of the control rods 20 enable him promptly to return the open gate or gates to the closed position.

It will, of course, be understood that the mechanism for raising and lowering the doors may be widely varied. If desired, the ratchet and pawl assemblies above described may be replaced by structures including brake drums and counterweights. In such event a counterweight can be employed to exert enough friction on the shaft 10 to leave the doors raised to any desired height by turning the wheel counterclockwise. It will therefore be understood that the claims, except so far as their language so restricts them, are not restricted to the precise structure herein shown.

I claim:

1. In a ballast distributing car for railroad track use, in combination with a car body, a chute adjacent each side of the car body and in communication with the interior of said car body, each chute including side walls, a front wall, and a downwardly inclined bottom wall, said walls defining a discharge opening along the lower end of the bottom wall, each chute being aligned transversely of said car body and having a closure for removably closing the discharge opening, actuating means for raising and independently variably positioning each closure to vary the extent of each opening above the rail including a manually rotatable control shaft, extending transversely of the car body and a flexible connection between said shaft and each closure, rotation of said shaft being effective, through said flexible connections, to raise said closures, means for locking the actuating means for holding the closures in a raised position, and means for re-

leasing said locking means including a rotatable release shaft parallel to and generally adjacent said control shaft, means for rotating said release shaft and an actuating lever on said release shaft for releasing said locking means.

2. The structure of claim 1 further characterized in that said locking means includes a ratchet connected to said control shaft and a pawl positioned to cooperate with said ratchet to lock said control shaft, said release shaft being positioned such that said actuating lever moves said pawl out of engagement with the ratchet.

3. The structure of claim 1 further characterized by a deflector intermediate the ends of each discharge opening and vertically aligned transversely of said discharge opening, each deflector being positioned to divide the flow of material through said discharge opening into a plurality of laterally divergent streams.
